UNITED STATES PATENT OFFICE

MELVIN B. SPRIGG, OF WESTON, WEST VIRGINIA

REFLECTOR

Application filed August 11, 1928. Serial No. 299,093.

The present invention relates to reflectors and while more especially intended for use as road and vehicle signs to indicate danger, is also well adapted for use as a display sign 5 in store windows and the like.

One of the primary objects of the invention resides in the provision of a reflector lens which is simple and inexpensive in construction and yet which so reflects the light projected upon it as to be seen at a much greater distance than lenses now in general use.

A further object of the invention consists in the provision of a reflector which utilizes colored glass discs, whereby a variety of different colors may be employed in a single unit.

Other objects and advantages of the invention will be apparent from the following description when taken in connection with the 20 accompanying drawings; in which

Figure 1 is a front elevation of a sign embodying the present invention, parts being broken away.

Figure 2 is a vertical sectional view taken 25 on line 2—2 of Figure 1.

Figure 3 is a fragmentary rear elevational view of the glass plate as shown in Figures 1 and 2.

Figure 4 is a sectional view taken on line 30 4—4 of Figure 3.

Figure 5 is a rear elevational view of a slightly modified construction of lens; and

Figure 6 is a sectional view taken on line 35 6—6 of Figure 5.

Referring to the drawings in greater detail, and especially to Figures 1, 2, 3 and 4, the numeral 1 designates a wooden frame in which the display sign or signal is mounted, and is provided with a backing 2 and a locking means 3 of any preferred type. It will be understood also that this frame may be made of metal, celluloid, or other desired material and may take any convenient form desired.

45 Mounted within the frame 1 is a transpar-

ent glass plate 4 which is provided with a raised or embossed portion 5 in the form of a letter or other design, as for example, "T", "A", or the like. Integrally cast with the plate 4 and raised portion 5 are a plurality of 50

rounded knobs or lenses 6 which are here shown as arranged in the form of the letters "T" and "A". In the rear of the plate 4 and directly in line with the knobs 6 are circular depressions each of which is substantially co-

extensive in area with the knobs. Mounted 55 within each of the depressions and secured therein by cement or the like are circular glass discs 7. These discs are formed of colored glass and it will be apparent that all of 60 the discs may be of a single color or a variety of colors may be employed where it is desired

to provide a pleasing or striking effect.

Behind the plate 4 and the attached discs 7 is placed a mirror or other reflecting surface 8 adapted to reflect back through the lenses 6 any light which may be projected onto the front of the sign. The reflected light through the discs 7 will, of course, assume the color or colors of the discs, while 70 the reflected light returning through the other portions of the plate 4 will be a plain white.

In this connection it should be noted that the portions of the plate 4 which are beyond 75 the borders of the symbols formed thereon, as for instance, that portion of the plate beyond the raised portions forming the letters "T" and "A" are rendered opaque by means 80 of a layer of opaque material such as paint, sheet metal, or the like, as indicated by the numeral 4'. Obviously, therefore, a brilliant reflected beam of light in the form of the symbols will be provided each time a beam of 85 light is projected onto the sign, and within the beam in intensified form will appear in colors the letter, word or other indicia as represented by the arrangement of the lenses 6.

In Figures 5 and 6 a slightly modified form of the invention is shown in which lenses 20 of relatively large radius are employed. This embodiment of the invention is provided with rearwardly projected knobs or extensions 21 which are in alignment with the lenses 20, and are of sufficient depth to take care of the extra focal length of the lenses. Colored glass discs 22 are provided for each lens 20 as well as individual reflecting surfaces 23, and these parts may be held in assembled relation by means of metal caps or the like 25 which engage about the exterior of the knobs 21. In other respects this form 15 of the invention is practically identical with that shown in Figures 1 to 4 inclusive.

The plates 4 with the lenses thereon may be cast or molded as an entire unit or may be formed in a plurality of sections, each section, for instance, taking the form of a letter of the alphabet. Such a method of production tends to low cost of manufacture, and this low cost also extends to the method in which the coloring is applied to the reflected light, namely, by the insertion of colored glass discs 7 in the recesses formed in the rear of the plate 4. Furthermore, a sign as thus constructed gives an unusually strong reflected light, and one which is extremely 30 attractive and striking in appearance due to the variety of reflected colors which may be provided in a single display.

In accordance with the patent statutes I have described what I now believe to be the 35 best embodiment of my invention, but I do not wish to be understood thereby as limiting myself or the scope of the invention, as many changes and modifications may be made without departing from the spirit of the invention; all such I aim to include in the scope 40 of the appended claims.

What I claim as new and desire to secure by Letters Patent is:

1. In a device of the class described, a glass 45 plate formed with a recess in the rear side thereof, an integral lens formed on the opposite side of said plate and in alignment with the recess, a disc of colored translucent material secured in said recess, and a reflecting 50 element positioned behind said disc.

2. In a device of the class described, a glass plate, a plurality of lenses formed on one side of said plate and arranged in the form of a symbol, discs of colored translucent material disposed on the opposite side of said plate and in alignment with said lenses, and a reflecting element operatively associated with said lenses.

3. In a device of the class described, a glass 60 plate, a plurality of lenses formed on one side of said plate and arranged in the form of a symbol, cylindrical recesses formed on the opposite side of said plate and in alignment with the respective lenses, a disc of 65 colored glass disposed in each recess, and a

reflecting element mounted behind said discs.

4. In a device of the class described, a glass plate, a raised or embossed portion on one side of said plate in the form of a letter or other symbol, a plurality of lenses formed on said embossed portion, cylindrical recesses formed on the opposite side of said plate in alignment with the respective lenses, a disc of colored glass disposed in each recess, and a reflecting element mounted behind said discs.
